WILSON E. SYMONS, OF NEW YORK, N. Y.

ELECTRIC WELDING-TOOL.

1,240,900.

Specification of Letters Patent. Patented Sept. 25, 1917.

Application filed February 21, 1917. Serial No. 150,095.

To all whom it may concern:

Be it known that I, WILSON E. SYMONS, a citizen of the United States, residing at New York, in the county of New York and 5 State of New York, have invented a new and useful Electric Welding-Tool, of which the following is a specification.

This invention has reference to electric welding tools for use in connection with arc 10 welding, and its object is to provide a tool, for the purpose, of convenient form for handling and containing control means within convenient reach of the operator, but so situated as to be free from liability of being 15 accidentally rendered active, or injured.

In accordance with the present invention the electrode holder includes a pistol-grip handle of hollow construction to contain a protected switch and also house both the 20 main and control conductors. The tool includes an electrode clamp capable of holding the electrode at different angles to the clamp while the clamp and handle are so united that they may be placed at different 25 angles one to the other and there held by yieldable means resistant to all ordinary distorting forces, but yieldable to a purposely applied force intended to readjust the clamp with relation to the handle. The temporary holding or locking means for the electrode clamp may be either elastically or frictionally held in adjusted positions.

The handle is provided with a switch for the distant control of the current generating set with which the handle is employed and the contact portion of the switch is entirely inclosed within the handle while manipulating portions of the switch are situated in the part of the handle constituting 40 the pistol grip in such position that an operator grasping the handle may readily move the switch to different operative positions. The manipulating portions of the switch, however, are so situated as to be entirely 45 protected from accidental contact.

The invention will be best understood from a consideration of the following detailed description, taken in connection with the accompanying drawings forming part 50 of this specification, with the further understanding that while the drawings show a practical form of the invention, the latter is not confined to any strict conformity with the showing of the drawings, but may be 55 changed and modified so long as such

changes and modifications come within the scope of the appended claims.

In the drawings:—

Figure 1 is a perspective view on a reduced scale of an electrode holder embodying the invention.

Fig. 2 is a longitudinal section of the handle portion of the electrode holder, the scale being about full size.

Fig. 3 is a view similar to Fig. 2 but including only a portion of the handle and showing a somewhat modified form thereof.

Fig. 4 is a section on the line 4—4 of Fig. 2, with the electric conductors omitted.

Fig. 5 is a section on the line 5—5 of Fig. 2.

Fig. 6 is a section on the line 6—6 of Fig. 2.

Fig. 7 is a face view of the fixed contacts of the switch and of the insulating support therefor.

Fig. 8 is a perspective view of the switch and central contact with the parts separated to better show the construction.

Fig. 9 is a perspective view of a spring used in conjunction with the switch.

Fig. 10 is an elevation of one member of the electrode grip or clamp.

Fig. 11 is a section of the electrode grip or clamp taken along the line 11—11 of Fig. 10.

Fig. 12 is a detail view similar in part to Fig. 4 showing a different means for mounting the electrode holder on the handle.

Referring to the drawings, there is shown a handle member 1 in the form of a hollow casting with two branches 2, 3, respectively, united at one end and there formed into a neck 4 and also united at the other end and formed into a casing 5. The member 2 of the handle is the grip member and the member 3 constitutes a conduit through which there may be passed an electric conductor 6 constituting one of the main conductors of the apparatus, and designed to carry heavy current. The member 2 of the handle not only constitutes the grip member but through it extend conductors 7 used for the control of the distant generating unit, such as is commonly employed in connection with electric welding of the type with which the tool of the invention is used. In the showing of Figs. 1 and 2 the neck 4 is made a continuation of the branch 2 of the handle. In Fig. 3 there is a neck 4^a made a continuation of 105

110

the branch 3 of the handle. Otherwise the structure of Fig. 3 may be like that of Fig. 2. In both forms the handle is of the pistol-grip type and the branches 2 and 3 are utilized for housing appropriate portions of the main and control conductors secured by a packing nut 4^b.

The pistol-grip handle, besides serving as a housing for portions of the conductors, has the advantage of conforming closely to the grasping hand and facilitates the manipulation of the tool by the operator.

The casing 5 has an open end 8 and is provided with a cap plate 9 which latter is conveniently held by screws 10 threaded through lugs 11 within the body of the handle, so that the cap plate 9 may be readily removed when desired. The cap plate is set into the casing 5 so that when secured in place its outer face is flush with the corresponding face of the casing, making a smooth and unobtrusive finish.

Extending through the casing 5 and traversing the side walls thereof is a bolt 12 upon which are mounted corresponding ends of legs 13 which together with jaws 14 constitute a clamp or electrode holder for an electrode 15.

In welding apparatus of the type to which the invention relates, the electrodes 15 are customarily metal wires of appropriate gage, of which No. 9, approximating five-thirty-seconds or .1483 of an inch in diameter is the size usually employed. Of course, it is to be understood that various sizes are used in accordance with the work to be done.

The jaws 14 are or may be in the form of blocks fast to the legs 13 at the ends remote from the bolt or pivot 12, and each jaw is formed with grooves 16 arranged at various angles with the grooves of one jaw matching those of the other, so that the electrode 15 may be held in the jaw in alinement therewith, or at right angles thereto, or in different angular relations to the length of the electrode holder. The legs 13 are secured together at a distance from the jaws 14 by a rivet 17 so that the jaws 14 are maintained in contact with some force, or may be separated for the insertion of an electrode 15, the approaching force exerted on the jaws being sufficient to hold the electrode 15 by elastic pressure. When it is desired to insert or remove an electrode the legs 13 may be readily forced apart at the jaw end for a distance sufficient to insert or remove the electrode.

The ends of the legs 13 remote from the jaws 14 are made divergent and enter the casing 5 where they are traversed by the bolt 12, such divergent ends being indicated at 18. These extensions 18 have passages therethrough of a size considerably greater than the diameter of the bolt 12, so as to accommodate insulating bushing 19 in surrounding relation to the bolt. Between each di-

vergent end 18 and the adjacent wall of the casing 5 the bolt 12 carries a spacer 20 of insulating material.

Also mounted on the bolt 12 and located between the extensions 18 is a block 21 which may be of metal and is separated from the adjacent walls of the extensions 18 of the legs 13 by washers 22 of insulating material. The end portions of the extensions 18 remote from the legs 13 are connected by a screw 23 insulated from the block 21, which it traverses, by a sleeve 24 of insulating material. The block 21 is thereby firmly connected with the legs 13 of the electrode holder, but is insulated therefrom at all points.

That face of the block 21 remote from the legs 13 is formed with notches 25 into any one of which a pawl 26 may enter, this pawl being carried by a spring strip 27 fast to one wall of the casing 5 and to the plate 9, respectively, by screws 28, or in any other appropriate manner. The pawl 26 being elastically mounted will yield to rocking movements of the legs 13 constituting the electrode clamping means when the force exerted is sufficient to overcome the spring 27. This permits the angular relation of the legs 13 to the handle portion of the device to be changed within considerable limits with the electrode clamping members made up of the legs 13 held in adjusted positions with sufficient firmness to prevent change of relation of the handle member of the device under ordinary conditions of use, and especially under the conditions existent when the device is being used for welding.

The adjustment afforded by the yieldable locking of the electrode carrier comprising the legs 13 and jaws 14, and the adjustment afforded by the numerous grooves 16 in the jaws 14 provide for all necessary changes of position of the electrode 15 with reference to the handle. This permits the adjustment of the electrode to the work to be done and greatly facilitates the use of the device.

Instead of providing the electrode clamp or carrier with elastically yieldable temporary holding means, the block 21 and spring 27 may be omitted and the bolt 12 replaced by an elongated rivet 12^a. Furthermore, the insulating washers 22 may then be replaced by an insulating spacer block 22^a. Otherwise, the structure may be the same as that already described and more particularly shown in Fig. 4. By making the connection provided for by the rivet 12^a sufficiently tight the electrode carrier will be held in different adjusted positions solely by friction, but this is effective for most conditions, and because of its simplicity is to be preferred.

In order to provide at the electrode holder means for the control of the current produced by a distant generating unit, a plate 29 of insulating material is made fast to 130

that wall of the casing 5 remote from the open end 8 thereof, such wall being indicated at 30. Screws 31 constitute a convenient means for securing the plate 21 to the wall 5 30. Secured to the plate 29 about midway of its width and near what constitutes the upper end of the plate in the ordinary operative position of the device, there is a conducting strip 32 shown separately in Fig. 8.

10 One end of this strip is formed into a sleeve 33 for the reception of one of the conductors 7 and the other end of the strip, which is extended centrally along the plate 29, is provided with a spread contact terminal 34. 15 The plate 32 may be made fast to the plate 29 by a screw 35 and at an appropriate location on the plate 32 it carries a pin 36 projecting therefrom toward the mouth 8 of the casing 5.

20 Projecting through the plate 29 near what constitutes the lower end thereof is a pivot pin 37 extending into the space between the branches 2 and 3 of the handle and suitably insulated from any contact with metallic 25 parts of the handle. Exterior to the casing 5 the pin 37 has fast thereto a manipulating handle 38 which may be in the form of a strip of sheet metal bent upon itself at the ends and held to the pin 37 by lock nuts 30 39. The handle member 38 is provided at the end remote from the pin 37 with a manipulating knob 40 so positioned as to be readily engaged by the finger or thumb of the operator when the hand is grasping the 35 member or branch 2 of the handle 1.

Within the casing 5 the pin 37 carries a switch arm 41 having an extension 42 terminating in wings 43 projecting laterally from the extensions 42, and between these 40 wings 43 the terminal portion of the arm 42 is formed with a notch 44 for a purpose to be described. The extension 42 is joined to the switch arm 41 by a pivot pin 45 and the switch arm 41 and extension 42 are held 45 in normal alinement by a spring 46 surrounding the pin 45 and having its opposite ends engaging the switch arm 41 and the extension 42, respectively.

The arrangement is such that when the 50 switch arm 41 is properly located it bears upon the contact terminal 34. Fast to the plate 29 by screws 47 or otherwise are contact terminals 48 each in the path of a respective one of the wings 43. Ordinarily the 55 pin 36 is lodged in the notch 44 and the spring 46 maintains the switch arm 41 in a central position, the switch handle 38 being then in a similar position. When the switch handle 38 is moved to one side or the other 60 of the central position the switch arm 41 participates in the movement, but the extension 42 is prevented from so moving by the pin 36, whereupon the switch arm and its extension break alinement at the pivot 45 65 until the angular relation of the extension

42 and arm 41 is sufficient to release the extension 42 from the pin 36. Then the spring 46 put under tension by the movement of the switch lever tends to return the extension 42 into alinement with the switch arm 41, thus 70 causing the extension 42 to snap against one of the contacts 48 producing a quick break and quick contact.

To maintain the switch in a central position there is provided a swing 47* surrounding the pin 37 which latter is provided with a head 48* having a groove 49 traversed by a portion of the spring 47 while the spring 47 has terminal portions 50 engaging in the plate 29.

The operation of the device is in the main similar to electric welding tools of the same general type as the invention, the current being fed to the electrode 15 by way of the conductor 6 and holder arms 13, while the 85 switch in the casing 5 is moved to one position or another to control the current fed to the electrode holder. The work is connected up to the other side of the circuit in the usual manner.

The tool is advantageous over other tools of a similar nature in providing great flexibility in the angular relation of the electrode with respect to the tool, so that the electrode may be properly directed to the work to be 90 performed without the necessity of the operator assuming an uncomfortable position, as would often be the case with electrode holders where the angular relation of the electrode to the holder cannot be varied.

Moreover, the pistol-grip form of the handle prevents fatigue and by making the handle hollow and housing portions of the conductors the latter are out of the way and the device is correspondingly lightened and utilized. The location of the controlling 105 switch inside of the handle and yet accessible to the hand of the operator avoids damage to the switch through accident or carelessness, no portion of the switch being exposed 110 at any outer surface of the handle.

The sleeve 33 has been described as receiving one of the conductors 7. The other two conductors, there being three of such conductors, are connected to the respective 115 terminals 48 by the screws 47, or in any other appropriate manner.

The conductor 6 is connected to a socket 51 on one end of a plate 52 carried by the bolt 12 in face to face contact with one of 120 the extensions 18 of the electrode holder. The plate 52 is insulated from the bolt 12 which passes through it by one of the washers 19 which is made long enough for the purpose.

In another application No. 170,221, filed May 22nd, 1917, there is shown and described an electric welding tool having features in common with the electric welding tool herein shown and described, and it is 130

to be understood that claims in this application are intended to be comprehensive enough in scope to cover those features which are common to both applications.

5. What is claimed is:—

1. An electric welding tool provided with a handle portion and an electrode holder mounted on the handle for movement into different angular relations thereto and provided with means whereby the electrode holder may be maintained in different adjusted positions against disturbing forces incident to the use of the tool. 10
2. An electric welding tool provided with a handle portion and an electrode holder mounted on the handle for movement into different angular relations thereto and provided with means whereby the electrode holder may be maintained in different adjusted positions against disturbing forces incident to the use of the tool, the electrode holder also being provided with means for setting and holding the electrode in different angular relations to the holder. 20
3. An electric welding tool having a hollow handle portion constituting a conduit for electric conductors, an electrode holder carried by the handle portion, and a controlling switch inclosed in the handle portion and having a manipulating part extending to the exterior of the handle portion and located interior to the outer surfaces of the handle portion. 30
4. An electric welding tool having a hollow pistol-grip handle with spaced portions constituting conduits for electric conductors, an electrode holder carried by the handle portion, and a controlling switch housed in the handle portion and provided with a manipulating member extending into the space exterior to the walls of the handle and located between the parts of the handle constituting the conduits for electric conductors. 40
5. An electric welding tool having a handle portion and an electrode holder pivotally mounted on and projecting from the handle portion with the electrode holder and handle portion in frictional engagement resistant to the displacing forces incident to the operation of the tool and yieldable to purposely applied forces for changing the angular relation of the electrode holder to the handle. 50
6. An electric welding tool having a handle member and an electrode holder carried thereby and provided with yieldable electrode holding jaws having a plurality of differently located electrode receiving portions for clamping the electrode in different angular relations to the holder. 60
7. In an electric welding tool, an electrode holder having electrode holding jaws with a normal tendency to approach and in such normally closed relation as to automatically clamp an electrode between them, said jaws being yieldable to a purposely applied separating force and also having a plurality of holding portions for the electrodes located in different angular relations to each other. 70
8. In an electric welding tool, a handle, and an electrode holder pivotally mounted thereon, said electrode holder comprising like joined members each terminating at one end in a jaw with the jaws in normally engaging opposed relation and coercively shaped to hold an electrode in different angular positions with reference to the holder and the members of the holder having the ends remote from the jaws divergent 80 and mounted in and insulated from the handle for movements about an axis to variously position the holder in different angular relations to the handle. 85
9. An electric welding tool having a hollow handle with spaced portions constituting conduits for electric conductors and of pistol-grip conformation, the spaced portions uniting in a casing open at the end remote from the spaced portions, and an electrode holder having one end mounted in the casing. 90
10. An electric welding tool having a hollow handle with spaced portions constituting conduits for electric conductors and of pistol-grip conformation, the spaced portions uniting in a casing open at the end remote from the spaced portions, and an electrode holder having one end mounted in the casing, the tool also being provided with an electric switch located within the casing and having a manipulating portion extending to the space between the two spaced members and there accessible. 95
11. An electric welding tool comprising a handle member and an electrode holder carried thereby, the handle member being in the form of a hollow casting with two branches in spaced relation united at the ends to constitute conduits for electric conductors, said casting being formed with a casing housing one end of the electrode holder and at a point distant from the casing provided with an outlet opening for electric conductors extending through the casting. 100
12. An electric welding tool comprising a handle member and an electrode holder carried thereby, the handle member being in the form of a hollow casting with two branches in spaced relation united at the ends to constitute conduits for electric conductors, said casting being formed with a casing housing one end of the electrode holder and at a point distant from the casing provided with an outlet opening for electric conductors extending through the casting and the branch of the casting remote from the casing being shaped to constitute a pistol grip. 110
13. An electric welding tool comprising a handle member and an electrode holder carried thereby, the handle member being in the form of a hollow casting with two branches in spaced relation united at the ends to constitute conduits for electric conductors, said casting being formed with a casing housing one end of the electrode holder and at a point distant from the casing provided with an outlet opening for electric conductors extending through the casting and the branch of the casting remote from the casing being shaped to constitute a pistol grip. 120
14. An electric welding tool comprising a handle member and an electrode holder carried thereby, the handle member being in the form of a hollow casting with two branches in spaced relation united at the ends to constitute conduits for electric conductors, said casting being formed with a casing housing one end of the electrode holder and at a point distant from the casing provided with an outlet opening for electric conductors extending through the casting and the branch of the casting remote from the casing being shaped to constitute a pistol grip. 125
15. An electric welding tool comprising a handle member and an electrode holder carried thereby, the handle member being in the form of a hollow casting with two branches in spaced relation united at the ends to constitute conduits for electric conductors, said casting being formed with a casing housing one end of the electrode holder and at a point distant from the casing provided with an outlet opening for electric conductors extending through the casting and the branch of the casting remote from the casing being shaped to constitute a pistol grip. 130

handle member, and an electrode holder carried thereby, the handle member being hollow with two branches in spaced relation and united at the ends, the space between the branches adapting the handle member to form a pistol grip, and said branches forming separate conduits for electric conductors, one of the ends of the branches having a single outlet opening for the electric conductors, while the other end serves as a support for the electrode holder, and an electric switch carried by the handle member and located within the same and having the manipulating portion protected by the handle member from accidental contact.

14. An electric welding tool comprising a hollow pistol-grip handle portion provided with a casing at one end, an electrode holder carried at one end in the casing formed on the handle, and an electric switch housed in the casing and provided with a manipulating portion exterior to the casing and adjacent to the gripping portion of the handle for manipulation by the hand of the operator while grasping the handle.

15. In an electric welding tool provided with a hollow handle and an electrode holder carried thereby, an electric circuit controlling switch having a switch arm and circuit terminals housed within the hollow handle with a manipulating member connected to the switch arm and exterior to the hollow handle and located in position to be manipulated by the hand of an operator grasping the handle.

16. In an electric welding tool having a

hollow handle and an electrode holder carried thereby, a circuit controlling switch having a rockable switch arm and a series of contacts with conductor receiving parts all housed within the handle and insulated therefrom and protected by the handle from access, and a manipulating member for the switch arm extending to the outside of the handle and located in position to be moved by the hand of the operator grasping the handle.

17. In an electric welding tool having a hollow handle and an electrode holder carried thereby, a circuit controlling switch having a rockable switch arm and a series of contacts with conductor receiving parts all housed within the handle and insulated therefrom and protected by the handle from access, and a manipulating member for the switch arm extending to the outside of the handle and located in position to be moved by the hand of the operator grasping the handle, the switch having means for constraining the switch arm to a central position and for temporarily holding it and yieldable to purposely applied forces tending to move the switch arm to other active positions.

In testimony that I claim the foregoing as my own, I have hereto affixed my signature in the presence of two witnesses.

WILSON E. SYMONS.
